UNITED STATES PATENT OFFICE.

WILLIS H. CARRIER, OF BUFFALO, NEW YORK, ASSIGNOR TO BUFFALO FORGE COMPANY, OF BUFFALO, NEW YORK.

NOZZLE-FLUSHING MECHANISM FOR AIR AND GAS WASHERS AND THE LIKE.

1,312,721.

Specification of Letters Patent.

Patented Aug. 12, 1919.

Application filed October 11, 1913. Serial No. 794,748.

To all whom it may concern:

Be it known that I, WILLIS H. CARRIER, a citizen of the United States, residing at Buffalo, in the county of Erie and State of New York, have invented a new and useful Improvement in Nozzle-Flushing Mechanisms for Air and Gas Washers and the like, of which the following is a specification.

This invention relates to improvements in air and gas washers and analogous apparatus in which air or gas is washed or conditioned by being brought into contact with water discharged from spray or distributing nozzles.

15 The objects of the invention are to provide efficient means for flushing the water discharge nozzles to prevent the same from becoming clogged by impurities in the water; also to provide efficient and practical means whereby the nozzles are flushed automatically at predetermined intervals of time, which can be readily controlled as may be desired or necessary; also to produce a flushing nozzle of simple and practical and 25 desirable construction.

In the accompanying drawings, consisting of three sheets:

Figure 1 is a fragmentary sectional plan view of an air or gas washing apparatus embodying the invention.

Fig. 2 is a longitudinal sectional elevation thereof.

Fig. 3 is a transverse sectional elevation thereof.

35 Fig. 4 is a fragmentary transverse sectional elevation thereof in line 4-4, Fig. 2.

Fig. 5 is an enlarged sectional elevation of one of the water discharge nozzles.

40 Fig. 6 is an enlarged section of the valve which controls the flushing of the nozzles.

Like reference characters refer to like parts in the several figures.

A represents the washing chamber of an air or gas washing or conditioning apparatus through which the air or gas may be caused to flow by any suitable means not shown, and B represents nozzles for discharging water into the chamber A for washing or otherwise conditioning the air or gas. C represents spaced zig-zag eliminator plates of ordinary construction for removing the free water from the air or gas before it leaves the chamber A.

55 Any suitable number and arrangement of the discharge nozzles B may be employed, depending upon the capacity of the appa-

ratus and the use for which it is intended. As shown, the nozzles are connected by lateral branches d and upright pipes d' to a main supply pipe d".

60 Each of the discharge nozzles is preferably constructed as shown in Fig. 5. As there shown the body of the nozzle is divided into two chambers b and b' by a transverse diaphragm b² of rubber or other suitable material, the body being preferably formed of two hollow shells or parts b³ b⁴ provided with flanges b⁵ which are connected by bolts b⁶ and between which the diaphragm is clamped and secured. The shell b³ is connected, preferably at one side, with the water supply pipe d and is provided with a tapered or contracted open end through which the water discharges. E represents a distributing disk which is located just in front of the discharge end of the nozzle so as to cause the water to spread and discharge in the form of a thin sheet through the narrow annular space between the disk and the end of the nozzle. The distributing 70 disk is secured to the outer end of a rod or stem e which extends into the nozzle and is secured at its inner end to the diaphragm b² which is adapted to be actuated to move the disk toward and from the end of the nozzle. 75 The area of the diaphragm b² exposed to the pressure of the water in the chamber b is larger than the area of the distributing disk E exposed to the water pressure and the pressure of the water in the chamber b, therefore, tends to move the disk inwardly and hold it normally close to the end of the nozzle, as shown in Fig. 5. The distance of the disk E from the end of the nozzle is regulated to control the discharge of water from 80 the nozzle by a suitable adjustable device, such, for instance, as a set screw G which limits the inward movement of the diaphragm and the disk E by engaging the inner end of the stem e. By adjusting the 85 set screw inwardly or outwardly the distance of the disk E from the end of the nozzle can be increased or decreased as may be desired. 90 H represents a pipe for admitting pressure, either liquid or fluid, from any suitable source to the chamber b' in rear of the diaphragm b² for actuating the diaphragm to move the disk E away from the end of the nozzle so as to permit a considerable volume of water to be discharged for flushing 95 the nozzle or clearing out any matter which may have collected in and obstructed 100

the narrow passage between the end of the nozzle and the disk E. If the pressure on the rear side of the diaphragm b^2 equals or exceeds the pressure of the water on the 5 front side of the diaphragm, the pressure of the water on the disk E will move the same outwardly. Thus the diaphragm can be actuated to move the disk E outwardly for flushing the nozzle by admitting to the 10 chamber b' water under the same pressure and from the same source as the water which is discharged by the nozzle. The admission of the pressure fluid to the chamber b' for flushing the nozzle can be controlled by any 15 suitable valve or device operated either by hand or automatically. Preferably, however, all of the nozzles B are flushed periodically by a common automatic controlling mechanism, the mechanism shown for this 20 purpose being constructed as follows:

The pipes H for the several nozzles B are connected by flexible hose h , upright pipes h' , and a pipe h^2 to a main pressure supply pipe h^3 provided with a valve I for controlling the pressure to all of the nozzles. The 25 valve I shown, see Fig. 6, slides in a casing i and is adapted when raised by a spring i^2 to cut off the fluid from the supply pipe h^3 and connect the pipe h^2 to a discharge opening i^2 to allow the water to drain from the 30 chamber b' . By depressing the valve the discharge opening i^2 is closed and the pressure fluid is admitted to the pipe h^2 and nozzle chamber b' .

35 K represents a dumping pan or receptacle arranged in the washing chamber A in position to catch water discharged from one or more of the nozzles B. This pan is secured to a rock shaft k provided with a weighted 40 arm k' which is normally adapted to hold the pan K in position to receive and retain the water. When sufficient water collects in the pan K to overcome the counterbalancing weight, the pan will tip and discharge the 45 water and by this movement actuate the valve I. When the pan is emptied the weight will again turn the pan to its receiving position, the weight being adapted to rest against a suitable stop or support k^2 when the pan is in its normal receiving position. L represents an adjustable shield or 50 deflector over the pan K. By adjusting this shield it is caused to cover the pan more or less, thereby determining the length of time required for enough water to collect in the pan to tilt it. The valve I can be actuated by the tilting of the pan K through any suitable connection. As shown the projecting end of the valve stem is engaged by a 55 lever or arm M which is pivoted at m on a bracket extending from the valve casing and is connected by a link m' to an arm on the rock shaft to which the pan K is connected.

When the pan is tilted by the weight of the water therein it depresses the lever against the action of the valve returning spring and moves the valve to connect the pressure supply pipe h^3 with the pipe h^2 leading to the nozzles thereby admitting pressure to the chamber b' of the nozzles. When the pan is 65 returned to its normal receiving position by its counterbalancing weight the valve is returned by its spring to a position in which it cuts off the pressure supply pipe h^3 and connects the pipe h^2 with the discharge opening i^2 , thus permitting the water to discharge through the pipe and valve from the chambers b' of the nozzles and relieving the 70 pressure on the rear side of the nozzle diaphragms b^2 .

80 By the described mechanism the nozzles will be flushed periodically whenever sufficient water collects in the pan K to tilt it, and the interval of time between the flushings can be governed by the adjustment of 85 the shield L. Manifestly various other mechanisms could be employed for periodically admitting pressure to the chambers b' of the nozzles for flushing the nozzles and this invention is not restricted to the particular mechanism described.

I claim as my invention:

1. In an air washing apparatus, the combination of a discharge nozzle for the washing liquid having a normally restricted discharge opening, a pan arranged to receive liquid discharged by said nozzle and to be moved by the weight of the liquid collected therein, means actuated by said pan when moved for enlarging the discharge opening 100 of said nozzle, and a shield for said pan which is mounted independently of the pan and is adjustable relatively to the pan to intercept more or less of the liquid going to said pan for varying the operating periods 105 of said pan, substantially as set forth.

2. In an air washing apparatus, the combination of a discharge nozzle for the washing liquid having a normally restricted discharge opening, a pivotally mounted pan arranged to receive liquid discharged by said nozzle and to be moved by the weight of the liquid collected therein, means actuated by said pan when moved for enlarging the discharge opening of said nozzle, and a pivotally adjustable shield over said pan for 110 regulating the delivery of liquid to said pan for varying the operating periods of said pan, substantially as set forth.

Witness my hand, this 7th day of October, 1913.
